UNITED STATES PATENT OFFICE.

IRA CUNNINGHAM AND HAYWOOD FLOWERS, OF GRAND SALINE, TEXAS.

WRENCH.

1,092,695.

Specification of Letters Patent.

Patented Apr. 7, 1914.

Application filed May 28, 1913. Serial No. 770,508.

To all whom it may concern:

Be it known that we, IRA CUNNINGHAM and HAYWOOD FLOWERS, citizens of the United States, residing at Grand Saline, in the county of Van Zandt and State of Texas, have invented a new and useful Wrench, of which the following is a specification.

The invention relates to improvements in wrenches.

- 10 The object of the present invention is to improve the construction of wrenches, and to provide a simple, efficient and comparatively inexpensive wrench of strong and durable construction, capable of instantaneous initial or preliminary adjustment to fit any sized nut or other object within its capacity, and capable also of a quick final adjustment to engage the object operated on firmly and securely.
- 20 With these and other objects in view, the invention consists in the construction and novel combination of parts hereinafter fully described, illustrated in the accompanying drawing, and pointed out in the claims here- 25 to appended; it being understood that various changes in the form, proportion, size and minor details of construction, within the scope of the claims, may be resorted to without departing from the spirit or sacrificing 30 any of the advantages of the invention.

In the drawing:—Figure 1 is a side elevation of a wrench, constructed in accordance with the invention, taken at right angles to Fig. 2. Fig. 3 is a similar view, taken at right angles to Fig. 2. Fig. 4 is a transverse sectional view on the line 4—4 of Fig. 1. Fig. 5 is a detail sectional view of the sleeve. Figs. 6 and 7 are detail views, illustrating the construction of the coupling members for connecting the rotary sleeve with the sliding jaw and the sliding sleeve or casing.

Like numerals of reference designate corresponding parts in all the figures of the drawing.

In the accompanying drawing in which is illustrated the preferred embodiment of the invention, 1 designates a straight shank equipped at its outer end with a rigid jaw 2 and preferably rounded at the side edges, which are also provided with teeth 3 formed by cutting or recessing the side edges or faces and shouldered at the outer ends and adapted to be engaged by opposite spring actuated pawls 4, which lock a sliding jaw 5 against inward movement on the shank. The

sliding jaw 5, which has a flat engaging face to cooperate with a corresponding engaging face of the rigid jaw 2, is provided with an opening 6 to receive the shank and has a hollow extension 7. The hollow extension or lower portion of the sliding jaw is provided at opposite sides with corresponding inclined or angularly disposed edges 8, and has opposite vertical shoulders 9 located at the side edges of the shank and extending from the upper end of one inclined side edge 8 to the lower end of the other inclined side edge 8. The inclined or angularly disposed edges of the sliding jaw are engaged by opposite cam edges 10 of a rotary cylindrical adjusting sleeve 11, mounted on the shank between the sliding jaw and a sliding sleeve or casing 12 and having a bearing against the rounded side edges of the shank. The inclined upper 75 or outer cam edges 10 of the adjusting sleeve 11 correspond to and are coextensive with the inclined or angularly disposed edge 8 of the sliding jaw, and the said sleeve, which is adapted to take up the slack after a preliminary or initial adjustment of the wrench, is provided at the ends of the cam edges with vertical shoulders 13 adapted to engage the vertical shoulders 9 of the sliding jaw, which limits the rotary movement 80 of the sleeve in one direction. After a quick adjustment of the sliding jaw by the means hereinafter described, the slack take-up sleeve 11 is adapted to be partially rotated to cause its cam edges to engage the sliding 85 jaw and force the same tightly against a nut or other object operated on by the wrench. The outer face of the sleeve is preferably milled, as shown, or otherwise roughened to enable it to be conveniently grasped and rotated.

The lower or inner end edge 14 of the adjusting sleeve is transversely arranged in a plane at right angles to the shank, and it fits against the upper edge of the slideable 100 sleeve or casing 12, which is also straight, as shown. The slideable sleeve or casing which is provided with an approximately cylindrical outer portion has its intermediate portion enlarged to form interior recesses 105 to receive engaging portions of pawls 16, pivoted by pins or rivets 17 in the intermediate enlarged or laterally extended portions of the sleeve or casing 12 and having outer operating arms 18, arranged at an obtuse 110 angle to the inner engaging arms and projecting outwardly through openings 19 in

the laterally enlarged portions of the sliding sleeve or casing. The inner engaging arms are each provided at their ends with a pair of teeth 20 for simultaneously engaging two of the side teeth of the shank. The engaging arms or portions of the pawls are urged toward the side edges of the shank by coiled springs 21, interposed between the opposite side faces of the upper portion of the sliding sleeve and the upper arms of the pawls. The upper or outer operating arms are adapted to be readily grasped and compressed between the thumb and one of the fingers of one hand, and when the engaging portions 15 of the pawls are swung outwardly beyond the straight side edges of the shank, the rotary sleeve and the sliding jaw are adapted to be moved readily in either direction to arrange the engaging portion of the sliding 20 jaw the proper distance from the fixed jaw 2.

The sliding jaw is coupled to the slack adjusting sleeve by means of opposite longitudinally disposed coupling members 22, fitted flat against the side faces of the shank 25 and provided with upper and lower lugs 23 and 24 engaging, respectively, the sliding jaw and the rotary sleeve. The sliding jaw is provided with interior longitudinal grooves 25 to receive the upper or outer portions 30 of the coupling members 22, and it has openings 26 at the outer ends of the grooves for the reception of the upper or outer lugs 23. The lower or inner portions 27 of the coupling members are rounded and extend 35 into the rotary sleeve and form bearings at the opposite flat side faces of the shank for the said rotary sleeve. The rotary sleeve is provided with interior inclined or spirally arranged grooves or ways 28, disposed in parallelism with the cam edges of the rotary sleeve and adapted to permit the adjustment of the rotary sleeve and the corresponding inward or outward movement of 40 the sliding jaw without affecting the connection between the inner ends of the coupling members 22 and the rotary sleeve. The lugs 24 at the inner ends of the coupling members are arranged at an angle or inclination to correspond with that of the inclined 45 or spirally arranged grooves of the rotary sleeve. The rotary sleeve is also coupled to the sliding sleeve or casing by inner or lower coupling members 29, having terminal lugs 30 and 31. The upper or outer lugs 30 50 of the coupling members 29 extend into the lower or inner end of the rotary sleeve and engage opposite transversely disposed grooves or ways 32 formed in the inner face of the sleeve 11. The outer portions of the coupling members 29 are also rounded at 55 to form bearings for the lower portions of the rotary sleeve. The lower coupling members 29 are also arranged in grooves 34 of the upper portion of the sliding sleeve or 60 casing 12, which is provided at the lower 65

ends of the grooves 34 with openings 35 for the reception of the lower lugs 31. The coupling members swivel the rotary sleeve to the sliding jaw and to the sliding sleeve or casing and connect the said parts and hold the same together in the adjustment of the 70 sliding jaw.

The shank of the wrench is provided at one side with suitable graduations 36 preferably in inches and fractions of an inch to 75 form a rule and to enable the size of a nut or other object to be ascertained without employing calipers for this purpose. The series of teeth terminate short of the inner end of the shank, which is smooth to form a handle, 80 and the shank is preferably provided at its handle portion with a screw 37, projecting slightly and adapted to form a stop for retaining the sliding jaw and the rotary and sliding sleeves on the shank.

What is claimed is:—

1. A wrench including a shank having a fixed jaw, a sliding jaw movable along the shank, a casing slideable on the shank and having a substantially cylindrical outer portion and provided with an intermediate enlarged portion having openings, the inner and outer portions of the casing being closed at the side edges, pawls mounted within the casing and having inner ends located within the inner portion thereof and engaging the shank to lock the casing against inward movement, said pawls having operating portions extending through the openings of the intermediate portion of the casing, springs interposed between the projecting portions of the pawls and the outer portion of the casing for holding the pawls normally in engagement with the shank, and a rotary sleeve swiveled to the cylindrical portion of the casing and to the sliding jaw and having a cam edge for engaging the latter. 95

2. A wrench including a shank having a fixed jaw, a sliding jaw mounted on the shank and having interiorly arranged longitudinal grooves and provided at the outer ends thereof with openings, a rotary sleeve mounted on the shank and having opposite cam edges for actuating the sliding jaw, 110 said sleeve being also provided with inclined or angularly disposed grooves or ways, coupling members mounted in the longitudinal grooves of the sliding jaw and having outer terminal lugs to engage the 115 openings thereof and provided at their inner ends with lugs engaging in the grooves or ways of the rotary sleeve, and means for holding the rotary sleeve against inward movement on the shank. 120

3. A wrench including a shank having a fixed jaw, a sliding jaw mounted on the shank, a rotary sleeve having a cam edge for actuating the sliding jaw and provided with transversely disposed grooves or 125

ways, a casing slideable along the shank and having means for engaging the same, said casing being also provided with interiorly arranged longitudinal grooves and having 5 openings at the inner or lower ends thereof, and coupling members arranged in the longitudinal grooves of the casing and provided with terminal lugs engaging the openings of the casing and the transverse grooves

10 or ways of the sliding sleeve.

4. A wrench including a shank having a fixed jaw, a sliding jaw mounted on the shank, a rotary sleeve having a cam edge for actuating the sliding jaw, said rotary 15 sleeve being provided with interiorly arranged inclined and transversely disposed grooves, coupling members carried by the sliding jaw and the casing and having rounded portions extending into the rotary 20 sleeve and provided with terminal lugs engaging in the said grooves, and means carried by the casing for engaging the shank.

5. A wrench including a shank having a fixed jaw, a sliding jaw mounted on the

shank and having an interiorly arranged 25 longitudinal groove, a casing slideable along the shank and provided with means for engaging the same and having an interiorly arranged longitudinal groove, a rotary sleeve arranged on the said shank between 30 the casing and the sliding jaw and provided with a cam edge for actuating the sliding jaw and having interior transversely disposed grooves, and interiorly arranged longitudinally disposed coupling members fitted 35 in the said grooves and provided with means for engaging the jaw and the casing, said coupling members also extending into the rotary sleeve and provided with means for engaging the grooves thereof. 40

In testimony, that we claim the foregoing as our own, we have hereto affixed our signatures in the presence of two witnesses.
